CLAIM

The ornamental design for a pill organizer calendar, as shown and described.

DESCRIPTION

FIG. 1 is a top plan view of a pill organizer calendar showing our new design;

FIG. 2 is a front elevational view thereof;

FIG. 3 is a bottom plan view thereof;

FIG. 4 is a rear elevational view thereof; and,

FIG. 5 is a left side elevational view thereof; the right side elevational view being a mirror image thereof.

Fig.1.

Fig.2.

Fig. 3.

Fig. 4.
